UNITED STATES PATENT OFFICE.

LUDWIG BACHRICH, OF VIENNA, AUSTRIA-HUNGARY.

APPARATUS FOR STERILIZING LIQUIDS.

SPECIFICATION forming part of Letters Patent No. 642,948, dated February 6, 1900.

Application filed November 7, 1899. Serial No. 736,138. (No model.)

To all whom it may concern:

Be it known that I, LUDWIG BACHRICH, mechanical engineer, of Vienna, Austria-Hungary, have invented certain new and useful 5 Improvements in Apparatus for Sterilizing Liquids, of which the following is a specification.

This invention relates to improvements in apparatus for sterilizing liquids—such as 10 wine, beer, milk, and the like—in a more perfect and economic manner than used until now, this result being attained by a new and useful 15 combination of one part of apparatus containing the liquid to be sterilized with a second similarly-constructed part of apparatus, the object of which is to receive and to preserve under pressure and in an unaltered condition that quantity of the liquid under treatment which by the expanding action of heat 20 is forced out of the main part of apparatus first mentioned.

The object of the present invention is to provide an apparatus whereby the sterilization of liquids is effected in accordance with 25 the requirements by the coöperation of two cylinders of different size, the larger one of which is completely filled with the liquid to be sterilized, while the smaller one contains compressed sterilized air or carbonic-acid gas 30 or the like. Despite the pressure of dilatation produced at the beginning of the operation both cylinders are allowed to rotate while heat is being applied. After exceeding a maximum of pressure—say, for instance, of ten 35 atmospheres—communication between the two cylinders is established by means of a valve, and the smaller cylinder receives that volume of liquid which is forced out by dilatation of the liquid in the larger cylinder.

40 This combination of two cylinders presents the advantage of allowing simultaneous application of heat and high pressure, quick heating and cooling, and rotation for the purpose of uniformly agitating the liquid and 45 equalizing its temperature throughout the whole volume; moreover, avoiding all loss of liquid, as that portion which is separated by dilatation is preserved for the next operation—that is to say, it will be returned into 50 the large cylinder before the next operation is commenced. By completely filling the large cylinder the expansion of the liquid in the

same produces from the very commencement of heating so high a pressure that no vapors can be formed at all, and therefore no escape 55 of the gases contained in the liquid can take place. Consequently all gases remain dissolved in the liquid. After the heat and high pressure have been allowed to act simultaneously for a certain lapse of time for the purpose of completely destroying all micro-organisms—such as yeast, bacteria, &c—suspended in the liquid, the latter is all at once cooled down.

All the surfaces which come into contact 60 with the liquid are completely lined with an alloy of precious metals, so as to prevent any alteration of the liquid by oxid of metal, which would doubtless take place if iron, copper, zinc, lead, or the like were used.

70 The accompanying drawings illustrate the construction of my improved apparatus.

Figure 1 is a side view, partly in section; and Fig. 2 an end view. Fig. 3 is an enlarged section on line 3 3 of Fig. 1, and Fig. 4 is a 75 section on line 4 4.

The apparatus consists, essentially, of two double-walled cylinders *a* *b*, capable of rotating about their longitudinal axes and placed lengthwise one above the other, both of which 80 contain a system of heating-pipes and are connected with one another by a non-rotating conduit *e*, in which a valve *v*, normally held closed by pressure in cylinder *b* and pipe *e*, is inserted. The upper cylinder *a* is supported by rollers *f* and has a toothed rim *g* engaging the gear *h*, by means of which rotary movement is transmitted to the said cylinder from the pulley *i*. The toothed rim *g* is in gear with a toothed rim *k* of the smaller 85 cylinder *b*, supported by a frame of any suitable construction, thereby also rotating this cylinder.

The liquid to be sterilized is introduced into the cylinder *a* at a tap *l* and withdrawn therefrom through the same tap after sterilization has been effected, while the smaller cylinder *b* is filled with carbonic-acid gas or compressed sterilized air.

Heating liquid or steam is admitted by the 100 pipe *m* into the space on one side of the longitudinal partition *4* between the two walls of cylinder *a* and passes through pipe *n* into the chamber *o* and on into the tubes *c* to chamber *o'*

on the opposite side of the partition 5, thence through the pipe *p* into the space between the two walls of the cylinder on the other side of partition 4, and leaves the apparatus by the 5 pipe *q*. In a similar manner the heating liquid or steam is conducted through pipes *d* and between the two walls of the smaller cylinder *b*, as indicated by pipes *m' q'*, which correspond in their connection and use to pipes 10 *m q*. Sterilization now proceeds in the afore-described manner. Any escape of gases which might take place at the end of the operation from the cooled liquid into the vacuum naturally formed above the latter in consequence 15 of the cooling will be prevented by allowing compressed air or carbonic-acid gas to enter and fill the said vacuum as it is formed.

The herein-described apparatus provides for the absence of air from the larger cylinder—*i. e.*, the sterilizing-cylinder—and this 20 absence of air is insured by completely filling the larger cylinder with the liquid to be sterilized and also by pumping out the air contained in the liquid in the case of, for instance, 25 milk.

By completely filling the larger cylinder of my apparatus the pressure of dilatation may safely and without any danger for either the liquid contents or the apparatus be allowed 30 to increase to the desired maximum, there being also no necessity for any extraordinarily strong construction to guard against fluctuations of pressure which may possibly occur. In addition my improved apparatus presents 35 the advantages of momentary heating up and cooling down, thorough mixture by rotation, prevention of all loss of gas, and employment of silver-plated surfaces.

Having now particularly described and ascertained the nature of my said invention and in what manner the same is to be performed, I declare that what I claim, and desire to secure by Letters Patent, is—

1. The combination, in apparatus for sterilizing, of the double-walled cylinder *a*, means for rotating it, an inlet *m* for a heating medium to the space between the walls of said cylinder at one end, an outlet *q* from said space, pipes *c* within the inner cylinder, pipe 45 *n* between said space and one end of each of pipes *c*, pipe *p* between the other ends of said pipes *c* and said space, another cylinder, *b*, means for rotating cylinder *b*, a pipe *e* connecting the central part of cylinder *a* to cylinder *b*, and a pressure-valve *v* in pipe *e* adapted to open outward when pressure exceeds a predetermined limit in cylinder *a*.

2. The combination, in apparatus for steril-

izing, of cylinder *a* having an annular space for a heating medium, an inlet *m*, and outlet 60 *q* for such medium, said cylinder having also space for material to be sterilized, a second cylinder *b*, a pipe *e*, communicating with cylinders *a*, *b*, through their axes so that the cylinders can rotate, means for rotating the 65 cylinders, and a valve *v* in pipe *e*.

3. The combination, in apparatus for sterilizing, of cylinder *a* having an annular space for a heating medium, an inlet *m* and outlet 70 *q* for such medium said cylinder having also space for material to be sterilized, several pipes *c* also for heating medium and extending from one end to the other and back again of the space for the material to be sterilized, a second cylinder *b*, a pipe or passage *e* communicating with cylinders *a*, *b* through their axes, means for rotating the cylinders, and a valve *v* in pipe *e*.

4. The combination of the double-walled cylinder *a*, means for rotating it, an inlet *m* 80 for a heating medium to the space between the walls of said cylinder at one end, an outlet *q* from said space, pipes *c* within the inner cylinder, pipe *n* between said space and one end of each of pipes *c*, pipe *p* between the 85 other end of pipes *c* and said space, another cylinder *b*, means for rotating cylinder *b*, a pipe *e* connecting the central part of cylinder *a* to cylinder *b*, a pressure-valve *v* in pipe *e* adapted to open outward when pressure exceeds a predetermined limit in cylinder *a*, cylinder *b* serving also to hold compressed air or gas, the cylinders and other parts in contact with material being sterilized having 90 a protected metal plating.

5. The combination of the double-walled cylinder *a*, means for rotating it, an inlet *m* for heating fluid, an outlet *q*, a partition dividing the space between the double walls of cylinder *a* between said inlet and outlet, pipes 100 *c* within cylinder *a*, chambers *o*, *o'*, pipes *n* and *p* connecting with opposite ends of pipes *c* and with chambers *o*, *o'*, cylinder *b*, a connection therefrom to the interior of cylinder *a*, a pressure-valve in said connection adapted 105 to open outward when pressure exceeds a predetermined limit in cylinder *a*, and means for rotating cylinder *b*.

In witness whereof I have hereunto signed my name, this 24th day of October, 1899, in 110 the presence of two subscribing witnesses.

LUDWIG BACHRICH.
